UNITED STATES PATENT OFFICE.

CHARLES PISSAHL, OF CHICAGO, ILLINOIS.

CHRISTMAS-TREE HOLDER.

No. 848,850.

Specification of Letters Patent.

Patented April 2, 1907.

Application filed October 6, 1906. Serial No. 337,670.

To all whom it may concern:

Be it known that I, CHARLES PISSAHL, a citizen of the United States, residing at 215 School street, Chicago, in the county of Cook and State of Illinois, have invented certain new and useful Improvements in a Christmas-Tree Holder, of which the following is a specification.

This invention has relation to standards for upright articles—such as poles, standards, flags, or trees—which are to be temporarily sustained in an upright position, and has for its object to provide a stand for such articles which shall be inexpensive, light in weight, and rigid in construction and which is generally known as a "Christmas-tree holder." It is well understood that in the provision of such an article as a Christmas-tree holder generally a very heavy article, such as a tree, must be sustained in a practically absolute upright position by a base which, while in itself sufficiently rigid to sustain a tree in this upright position, yet must be of a comparatively light and cheap construction.

Having the above object in view, my invention consists in the construction of a standard or base, which I will designate as a "Christmas-tree holder," of wood or metal, preferably a casting or drop-forging, forming the base proper, to which are attached adjustable brackets designed and adapted to accommodate the bases of trees of different diameters.

My invention therefore consists in a Christmas-tree holder having a rigid base and sliding brackets adjustably attached thereto.

My invention still further consists in the provision of a Christmas-tree holder consisting of a rigid cast-iron base provided with adjustable and removable brackets designed and adapted to grasp the base of the tree on opposite sides thereof.

My invention still further consists in the construction, combination, and arrangement of parts herein described and illustrated, and more specifically pointed out in the plans.

In the accompanying drawings, which form a part of this specification, Figure 1 is a perspective view of the complete holder with a tree in position. Fig. 2 is a perspective view of one of the upper brackets, and Fig. 3 a like view of one of the lower brackets.

The base 1 consists of a single casting or

forging having the arms 2, 3, 4, and 5, each 55 arm extending out from the center 1 and ending in a foot 6 6 6.

The casting is formed with a central orifice 7 for the reception of the lower end of a tree or other objects to be supported in the holder. 60

Two of the arms 2 4 are each provided with orifices for the passage of bolts 8 9, which pass from the bottom of the standard through the slots 10 in each of the gripping devices or brackets 11 12. The brackets 11 65 rest upon the upper face of the arms 2 4 and are provided with L-shaped ends 13, having jaws 14 to embrace the lower end of the tree, while the brackets 12 rest upon the upper surface of the brackets 11 and are likewise 70 provided with L-shaped ends arising a short distance above the jaws or gripping ends of the brackets 11, so as to grasp the tree some distance above the jaws of the brackets 11.

The bolts which pass through the base 75 and the slots 10 are provided with nuts 8', which bear down upon the upper surface of the bracket 12 and draw the two brackets and the base into contact.

It will be readily seen from Fig. 1 that 80 when the nuts 8' are released and the brackets 11 12 drawn back to the extremity permitted by the slots 10 that a tree-trunk can be inserted in the orifice 7. The two brackets 11 12 on each side of the base are 85 then drawn forward to embrace the body of the trunk, and by tightening the nuts 8' they are held firmly in position and the tree rigidly retained upright.

It is well known that the ordinary pine 90 tree used as a Christmas-tree is of varying diameter and that but very few, if any, of them are absolutely straight even for a short distance, and I have provided for this by permitting the adjustment of any of the 95 four brackets independently of the others, and this I consider a very important feature, as it permits a tree of practically any deviation from a straight line in its lower portion of the base to be rigidly sustained in a horizontal position. 100

Having thus described my invention, what I declare new is—

1. A stand comprising a base, and a plurality of sets of independently-adjustable 105 gripping devices mounted thereon, the devices of each set being slidable one on the other and arranged with their biting ends at

different heights to grip the object to be supported at a plurality of points vertically separated from each other.

2. A stand comprising a base, a set of diametrically-disposed gripping devices mounted thereon, a second set of diametrically-disposed gripping devices mounted for adjustment independently of the first set, the devices of each set being arranged with slides in a direction transverse to the axis of the objects to be supported, and a common means for securing each set of devices to the base.

3. A stand comprising a base having radially-disposed arms, a plurality of pairs of gripping devices on diametrically-disposed arms of the base and provided with longitudinal slots, and means extending through the slots for securing the gripping devices to the arms for independent radial adjustment.

4. In a "Christmas-tree holder" the combination with the base formed of a single casting having arms and a central orifice, of two pairs of adjustable L-shaped members resting upon said base, bolts passing through orifices in the base and slots in the members and adjusting-nuts upon said bolts which bear upon the top members and binding the members and base together.

5. A stand comprising a base provided with a plurality of radial arms, a pair of radially-adjustable gripping members mounted on the arms, and having jaws on their inner ends, a second pair of radially-adjustable gripping members on the base, and a common

means for securing corresponding members 35 of the pairs to the base.

6. A stand comprising a base provided with a central opening for receiving the bottom end of the object to be supported and with a plurality of radially-extended arms, a set of gripping devices mounted on the base and adjusted inwardly and outwardly with respect to the opening for engaging the object, and another set of gripping devices similarly adjustable and arranged with their inner ends to engage the said objects above the point of engagements of the first set.

7. A stand comprising a base provided with a central opening for receiving one end of the object to be supported and with a plurality of oppositely-extending arms, a pair of oppositely-disposed gripping devices radially adjustable on the base and having their inner ends formed into jaws for engaging the said objects, at one side of the base, and a second set of gripping devices adjustably mounted on the base and having their inner ends formed into jaws arranged to grip the said object at another point thereon axially spaced from the point of engagement of the first jaws.

In testimony whereof I have signed my name to this specification in the presence of two subscribing witnesses.

CHARLES PISSAHL.
